FRANZ PUENING, OF O'HARA TOWNSHIP, ALLEGHENY COUNTY, PENNSYLVANIA,
ASSIGNOR TO THE KOPPERS COMPANY, A CORPORATION OF DELAWARE

PREHEATING SYSTEM

Application filed July 20, 1927. Serial No. 207,043.

My invention relates to preheating systems, and particularly to preheating systems for preparing coal for carbonization in coke ovens or other carbonizing apparatus.

5 My invention has, for one of its objects, to provide a preheating system of large capacity that operates continuously to preheat and prepare coal to be supplied to coke ovens and the like.

10 Another object of my invention is to provide a preheater that is relatively small and inexpensive by reason of its comprising compact groups of heating flues through which the entire stream of coal moves uniformly 15 at such speed that local overheating is avoided.

A further object of my invention is to provide a preheater in which previously preheated coal is mixed with the wet unheated 20 coal whereby a portion of the moisture of the latter is initially evaporated and the temperature of the mixture is maintained above that at which water vapor condenses so that the vapors from the preheater do not condense 25 upon the incoming coal and clogging of the stream of coal is thereby avoided.

20 Another object of my invention is to provide preheating apparatus wherein the material to be treated follows such course through 30 the preheater that substantially the entire mass comes in contact with the heated portions thereof.

35 A further object of my invention is to provide apparatus for preheating coal in which gases of relatively high temperature may be employed without damage to flues of metal or other material adapted for lower temperatures.

40 A still further object of my invention is to provide a simple and efficient means whereby waste gases may be employed to protect surfaces of non-refractory materials from gases of combustion.

45 It has been demonstrated that coal or other carbonaceous material that is supplied to coke ovens or other carbonizing apparatus may be more easily carbonized if the coal has been heated to desired or predetermined temperatures before being supplied to the coke ovens.

50 It has been found, for example, that the time

required for coking may be materially reduced and that in some cases the efficiency of the system is materially increased when dry and heated coal is supplied to the carbonizing apparatus. It has also been found that 55 an improvement in coke structure may result from preheating the coal.

Preheating systems have been proposed heretofore but they have not, in general, been of a type suitable for treating large 60 quantities of coal.

It has heretofore been difficult to build preheaters of reasonably small or compact size. If, for example, coal were passed through a vertical tube or shaft that is heated on 65 the outside, the coal would become heated somewhere in the middle portion of the shaft and give off water vapor. The vapor would force its way both upwardly and downwardly, with the result that the portion of the 70 vapor going upwardly would condense in the colder portions of the incoming coal. The original raw coal containing some moisture would then become so wet, that it would clog the shaft and cease to flow downwardly. In 75 order to overcome this condition, it has been necessary to use shafts of a very considerable diameter through which a heavy column of very wet coal is able to pass down due to its weight, and in spite of its wetness. However, shafts of such large diameter occupy 80 much space and the preheaters are very bulky and expensive.

This same condition of course also prevails if coal is passed through a tower containing 85 many horizontal heating flues. The coal somewhere in the center of the tower would give off its moisture in the form of vapor and this would partially condense in the upper part of the tower in the cold coal. In such 90 a tower with horizontal heating flues, the wet coal would, of course, still more easily clog the preheater than in straight vertical shafts, because of the many changes of direction 95 which the coal has to execute while descending.

It has also been difficult, if not impossible, to operate preheating apparatus efficiently by reason of the limitations as to fuel and temperatures that may be employed. For exam- 100

ple, if gases of combustion are used, such coal as may come directly in contact with flues, pipes, or similar apparatus that have been heated approximately to the temperature of gases of combustion, may be heated beyond the desired or predetermined temperature, with the result that the coal first becomes fused and adherent to the wall so that further passage of such coal would temporarily be blocked and that later actual coke formation would occur with the result that flow through the preheater may be completely stopped. At the same time the metal flues would become so overheated that they would soon burn out. Such partial carbonization may also result in loss of valuable gases, or other by-products.

In accordance with the present invention, I provide preheating apparatus to which coal may be supplied continuously at its receiving end and properly heated, or treated, coal may be withdrawn at the output end at a substantially uniform rate. The wet or unheated coal is intimately mixed with a relatively large quantity of heated coal, by means of which the untreated coal is initially heated before it enters the preheating apparatus.

The proportion of mixture between hot coal and cold or wet coal is such that the temperature to which the wet coal is preheated is so high that a portion of its moisture is evaporated and that the temperature of the mixture of hot coal and original cold coal is above the condensing point of water vapor when it comes into contact with the heating flues or enters into the spaces between these flues or into other narrow spaces. This mixture upon its descent through the preheater is met by water vapor coming from portions of the coal below, but since this mixture has a temperature above the condensing point for water vapor, the rising vapor cannot possibly condense upon the incoming mixture and thus the latter retains its mobility or fluidity, and descends through the narrow passages of the preheater without stoppage.

The preheating apparatus of my invention is also provided with means whereby the waste gases may be utilized to form a protecting layer or envelope for the entrance portions of the flues through which gases of combustion are circulated. Efficient means are also provided for insuring that substantially all of the coal being treated comes in contact with one or more of the flues.

In the accompanying drawings,

Figure 1 is a view, in vertical section along the line I—I of Fig. 2, of preheating apparatus constructed in accordance with my invention;

Fig. 2 is a similar view of the preheating apparatus, taken along the line II—II of Fig. 1;

Fig. 3 is an enlarged fragmentary vertical

sectional view on line III—III of Fig. 1 showing the arrangement of the flues;

Fig. 4 is an enlarged fragmentary view on line IV—IV of Fig. 5 of the entrance end of one of the flues; and

Fig. 5 is an enlarged fragmentary view, in longitudinal section on line V—V of Fig. 4, of one of the flues.

Referring particularly to Figs. 1 and 2, a preheating apparatus constructed in accordance with my invention comprises a vertically-extending heating chamber 1, that is preferably of rectangular cross-section and that is traversed by a comparatively large number of horizontally-extending flues 2. A combustion chamber 3, which may be supplied with fuel, such, for example, as coke, coal or other material, supplies gases of combustion for heating the flues 2.

A skip hoist mechanism 4 comprising "skips" or buckets 5 supplies coal to be heated in the heating chamber. A series of connected conveyors 6, 7 and 8 receive the treated material from the heating chamber and supply new material for mixture therewith in a manner to be hereinafter described.

A blower, or centrifugal pump 9 withdraws the spent or waste gases after they have traversed the flues 2 and supplies a portion of such gases to the entrance portions of the flues adjacent to the combustion chamber 3. An agitating mechanism for insuring the continuous passage of the coal through the heating chamber 1 comprises a plurality of vertically-extending rods 11 that are reciprocated by means of horizontally-extending members 12 that are provided with crank arms 13, which are connected to cranks 14, operated by gear mechanisms 15.

Referring particularly to Figs. 2 and 3, the transversely-extending flues 2 are arranged in horizontal rows, the members of the several rows being staggered with respect to adjacent rows. The upper side portions of all of the flues, except those of the upper row, are arranged with inclined portions of unequal lengths, whereby portions of the streams of coal are shifted into different relative positions with respect to the flues as the coal passes successive rows of flues.

Reference may now be had to Figs. 4 and 5, in which the details of the entrance end of one of the flues of the lower rows for receiving the hot gases initially are clearly shown. The entrance end 16 of the flue, which is hexagonal in cross-section and projects through the wall of the chamber, is partially covered by a metal plate 17 having a rectangular opening 18 of smaller cross-section than that of the flue. The plate 17, which is covered by refractory material 19, is spaced from the flue and is connected thereto by four metal lugs or projections 20 that are preferably welded in position. The arrangement just described for one of the flues is typical of the entrance end

of each of the flues adjacent to the combustion chamber 3, only a portion of the plate 17 and its refractory covering being shown in Figs. 4 and 5. A separate plate 17 is preferably provided for each of the flues.

Referring again to Fig. 1, it will be noted that the entrance ends of the several flues which communicate directly with the combustion chamber 3 are partially covered by the plate member 17 and the refractory material 19, referred to in connection with Figs. 4 and 5. A rectangular space between the plate 17 and the outside wall of the heating chamber 1 communicates with all of the flues that are covered by the plate 17 by means of a relatively narrow aperture 21.

The operation of the heating system will now be described. Gases from the combustion chamber 3 pass through the several rectangular openings 18 in the plate 17 and the refractory material 19 into the group of flues 2 that are connected to the combustion chamber. The combustion gases may have a temperature, for example, of 3,000° F. At the upper end of the heating chamber, the relatively cool flue gases are withdrawn through a pipe 23 that is connected to the blower 9 and are conveyed through pipes 24, 25 and 26 to the lower corners of the rectangular space between the plate 17 and the wall of the chamber 1. These gases are supplied also to the upper corners of the rectangular space by pipes 27 which connect to the pipe 24. A portion of the waste gases is allowed to escape through a vertically extending pipe 28. The waste gases from the blower 9 which are supplied to the aperture 21 may have a temperature of approximately 500° F.

The high-temperature gases from the combustion chamber 3 flow through the relatively small openings 18 into the central portions of the flues connected thereto. The waste gases supplied through the apertures 21 flow into the same flues around the edges thereof and form an envelope for the hotter gases, whereby damage to the walls of the flues is prevented. The resultant mixture of the gases has an initial temperature of approximately 1500° F., which may be safely withstood by the flue walls.

It will be noted that suitable baffles 30 and 31 are provided, whereby the hot gases are caused to take a tortuous path through the several groups of flues in series. When the gases emerge from the upper group of flues from which they are withdrawn by the blower 9, they have a temperature of approximately 500° F.

It may be assumed that a mixture of heated and untreated or unheated coal, or other material, is being supplied to the top of the heating chamber by the buckets 5 of the skip hoist mechanism 4, which empty into a suitable hopper 32. The material to be heated flows downwardly by force of gravity be-

tween the several flues 2. A portion of the coal is adjacent to the initial rows of flues and it is heated thereby. As the columns move downwardly, they are divided into unequal portions by the inclined sides of the succeeding row of flues, whereby coal that has not been heated directly by the flues is brought into engagement with the sides of the flues in the next row. In a similar manner, the columns of coal passing each row of flues are divided in such manner that substantially all of the coal is in contact with one or more of the flues during its downward passage.

In order to prevent the coal remaining stationary and becoming carbonized or excessively heated, the agitating mechanism comprising the reciprocating rods 11 may operate continuously to agitate the streams of coal in order that the latter may be kept in motion.

The speed at which the coal passes through the heating chamber is regulated by the several discharging rotors 33, which serve to support the coal in the heating chamber and discharge it into the hopper 34. The amount of coal passing through the heating chamber in a given time being regulated by the speed at which the discharge rotors are rotated. The hopper 34 guides the coal into the conveyor 7, which conveys it to the right, as viewed in Fig. 1. A portion of the heated coal, for example, one-fifth, is diverted into the conveyor 8, by means of which it is transported to a suitable storage chamber (not shown).

The conveyor 6, which is connected to a source of coal that is unheated and which contains moisture, supplies unheated coal to the conveyor 7 in an amount equal to that withdrawn by the conveyor 8. The unheated coal, which may constitute approximately one-fifth of the coal in the conveyor 7, is intimately mixed with the heated coal during its passage through the remainder of the conveyor 7. The mixture is then conveyed to the skip hoist mechanism, where it is transferred to two hoppers 36, each of which has a pivotally-mounted spout 37 that moves to the position indicated by dotted lines when the corresponding bucket 5 is elevated and that returns to its operative position when the bucket is again lowered. The buckets 5 carry the mixture of heated and unheated coal received from the hoppers 36 to the top of the preheater, where they empty into the hopper 32, connected to the top of the heating chamber 1.

During the period of time elapsing between the supplying of the unheated coal to the conveyor 7 and the elevation of the mixture to the top of the heating chamber 1, the added coal is dried and is partially heated, whereby it is in condition to flow freely through the heating chamber 1. It will be

understood that the proportion of unheated coal that is added may be varied in accordance with the condition of the unheated coal or with other operating conditions, in order to insure satisfactory and continuous operation of the preheater. Economical operation of the preheater would require that only such amount of coal be re-circulated as is necessary to insure that the mixture of both coals has a temperature sufficient to preclude condensation of moisture by the mixture.

10 The cycle of operations that have been described continue so long as the preheater is in operation. The treated coal that is withdrawn through the conveyor 8 is supplied to coke ovens or the like as desired and the supply to the conveyor 6 is added at substantially the same rate.

15 It will be noted that I have provided a preheater that may utilize gases of combustion without the employment of large quantities of refractory material, such as is usually necessary when gases of high temperature are involved. A relatively simple expedient of 20 providing initially an envelope of gases of moderate temperature insures that the walls of the flues will not be damaged.

25 I have provided, also, an arrangement of the flues in such manner and of such construction that the streams of coal flowing therebetween are divided in such portions that an equal distribution of the coal between the various rows of flues is insured whereby substantially all of the coal is in contact with one or more of the flues during 30 its passage through the heating chamber. The entire mechanism is substantially automatic, it being necessary only to regulate the amount of unheated coal to be added in accordance with the portion that is withdrawn and to regulate the proportion of waste gases 35 that are mixed with the gases of combustion in accordance with the temperature of the latter gases.

40 While I have described my invention as being particularly adapted for the preheating of coal prior to its being supplied to coke ovens for carbonization, it will be obvious to those skilled in the art to which my invention appertains that it may be employed in connection with any process wherein it is desired to heat coal or other material. For 45 example, it may be possible to heat the flues of the heating chamber to such temperatures that carbonization or distillation of non-coking coal, shale or lignite may be accomplished during its passage therethrough. The foregoing and other applications of my invention will occur to those familiar with apparatus 50 of this general type.

I claim as my invention:

1. In a heating system, the combination with a passageway for heated gases, of means for supplying gases at different temperatures thereto, said gases being so disposed initially

that the hotter gas is surrounded by a layer of gas of lower temperature.

2. In a heating system, the combination with a passageway for heated gases, of means for supplying gases at different temperatures thereto, said gases being so disposed initially 70 that the hotter gas is surrounded by a layer of gas of lower temperature, said means comprising a member having an opening in alignment with, but of smaller cross-section than, said passageway and said member being spaced from one end of said passageway to provide an opening therebetween.

3. In a heating system, the combination with a plurality of passageways for heated 80 gases, of means for supplying gases at different temperatures to each of said passageways, said gases being so disposed that at the entrance of each of said passageways the hotter gas is surrounded by a layer of gas of 85 lower temperature.

4. In a heating system, the combination with a plurality of passageways for heated gases, of means for supplying gases at different temperatures to each of said passageways, said gases being so disposed that at the entrance of each of said passageways the hotter gas is surrounded by a layer of gas of 90 lower temperature, said means comprising a structure having openings in alignment with, but of smaller cross-section than, said passageways, and said structure being spaced from the ends of said passageways to provide 95 openings communicating therewith.

5. In a heating system, the combination with a passageway for heated gases, of means for supplying gas at relatively high temperature to said passageway, and means for supplying a layer of gas at relatively low temperature gas between the high temperature gas and the walls of said passageway at the 100 entrance thereof.

6. The combination with a plurality of flues for gases and a plurality of sources of 105 gas of different temperatures, of means for directing the flow of said gases to said flues comprising a structure spaced from the ends of said flues to provide access of relatively low temperature gas to said flues at the peripheries thereof, said structure having 110 aligned openings of constricted cross-sectional area to admit relatively high temperature gas to the central portions of said flues.

7. In a heating system, a plurality of 115 spaced horizontal flues in staggered relation, said flues having sloping top portions of different lengths whereby streams of material passing between said flues are intermingled.

8. In a heating system, a plurality of rows 120 of spaced flues, the members of adjacent rows being in staggered relation and said flues having sloping top portions of unequal lengths whereby adjacent streams of material passing between said flues are variously intermingled.

9. In a heating system, a plurality of rows of spaced flues, the members of adjacent rows being in staggered relation and said flues having sloping top portions of unequal lengths, the flues of adjacent rows being oppositely arranged with respect to said top portions whereby streams of material flowing downwardly between said flues are intermingled to insure that unheated material is adjacent to said flues.
10. In a heating system, the combination with a plurality of flues and a source of gas at a relatively high temperature, of means for returning a portion of the waste gas from said flues at reduced temperature for mixture with the high temperature gas, and means for insuring a supply of the gas of reduced temperature for each of said flues comprising a foraminous structure spaced from the entrances of said flues, and means for conducting the waste gas between said structure and the entrances to said flues.
